GLEN L. POPE AND ABE COHEN, OF GRETNNA, NEBRASKA.

FASTENER FOR BARBERS' APRONS.

Application filed April 20, 1928. Serial No. 271,497.

This invention relates to a fastener for the neck piece of a barber's apron or hair cloth, and has for its principal object to provide such a construction for a fastener that it may be readily secured to an end-portion of the neck piece of the apron or hair cloth and will provide adjustments, so that the hair cloth or apron may fit closely upon large or small necks.

10 The invention has for one of its objects to provide a fastener which can be conveniently made, will be comparatively inexpensive in manufacture, will be convenient in use and will not become injured during the operation 15 of laundering.

15 The invention includes a flexible, elongated attenuated pad formed by winding a fabric strip upon itself in overlapped relation to form numerous pockets or detents at longitudinal intervals and adapted to be stitched to an end-portion of the neck-piece of the apron, whereby a hook secured upon an opposite end-portion of the apron may engage in a selected pocket for the purposes mentioned.

20 With the foregoing objects in view the invention presents a new and useful construction, combination and arrangement of parts as described herein and claimed, and as shown in the accompanying drawing, it being understood that changes in size, proportion and minor details may be changed as found to be of advantage, said changes being within the scope of the invention as claimed.

25 In the drawing, Fig. 1 is a broken away view showing the device applied to an end-portion of the neck piece of a barber's apron or hair cloth. Fig. 2 is a section on line 2—2 of Fig. 5. Fig. 3 shows a part of the fastener and a hook engaging one of the pockets. Fig. 40 4 illustrates the use of the fastener. Fig. 5 is an enlarged side view, showing a part of the fastener.

35 Referring now to the drawing for a more particular description, the fastener is shown and described in connection with a neck piece 45 of a barber's apron or hair cloth 7.

40 The fastener consists of a fabric strip which is wound longitudinally upon itself in overlapped relation to form numerous folds. The 50 width of the strip is not important but the number of folds should be sufficient to form a number of detents 8 adapted to be engaged by a hook 9, said hook being secured to an end-portion 10 opposite to the end-portion 11 upon which the fastener is secured.

55 By referring to Figs. 3 and 5 of the draw-

ing it will be seen that the pockets 8 are formed by winding a fabric strip upon itself to form folds, each fold being indicated at 12, one-half of one complete fold operating to form a pocket or detent 8 at the outer side of the fastener, and each member 8 having a rectilinear edge disposed approximately at right-angles to the fastener, a part 13 of each fold being disposed at the rear side of the fastener inclinedly or in angular relation to the one-half part of 12 of a fold as shown by dotted lines.

60 The winding of the strip mentioned may be readily accomplished, and for this purpose a narrow metallic or paste-board strip (not shown) being used to advantage, upon which the fabric strip may be wound, care being exercised in the winding so that the edges of the pockets will be disposed at right-angles to the fastener in forming one-half of each fold, the one-half 13 of each fold being disposed inclinedly to the half which forms the pockets as mentioned. The metallic or pasteboard strip is then drawn outwardly from the folds thus formed, and rows of stitches 14 are then provided for the fastener near the longitudinal edges thereof.

65 It will be understood that the fastener may be secured to one of the end-portions 7 opposite to the mounting of the hook 9 and that the pockets or detents 8, or any one of said pockets, may operate as a holder for the hook, and in operation the neck-piece of a hair cloth or apron may be disposed to fit snugly upon the neck since a suitable detent 8 may be selected to be engaged by the hook.

70 It will be understood that the fastener when completed will have the appearance of an elongated flexible pad, its thickness depending upon the width of the flexible strip used. It will be appreciated by those who use the fasteners that, on account of the construction described, the hook 9 will readily enter any selected holder 8, one reason being that the edges of the pockets will have a limited outward curvature, another reason being that the fastener will have a yielding surface similar to that of a pad or cushion, this result being caused by the numerous folds mentioned.

75 We claim as our invention,—

80 1. A fastener for the neck piece of a barber's apron, comprising a fabric strip wound spirally in overlapping relation upon itself to form numerous folds having exposed edges, rows of stitches near the ends of the folds connecting said folds with each other, each fold

between said rows of stitches providing a detent for receiving a hook.

2. In a fastener for an end-portion of a neck-piece of an apron, an opposite end-portion of the neck-piece being provided with a hook, a fabric strip wound spirally upon itself in overlapping relation and forming numerous folds each having an exposed edge, a pair of rows of stitches near the ends of the 10 folds connecting the folds one with another and connecting the folds to the neck-piece, each exposed edge of a fold providing a detent adapted to be engaged by said hook.
3. In a fastener for a barber's apron, an 15 elongated, attenuated flexible pad consisting of a fabric strip wound spirally to form numerous folds overlapping each other and adapted to be secured to the apron, rows of stitches connecting the folds one with another, the overlapping part of each fold forming 20 a holder-member adapted to be engaged by a hook.
4. A fastener for connecting two opposed

parts of an apron, one of said parts being provided with a hook, a strip of fabric wound spirally to provide a plurality of overlapping folds and secured to the opposed part of the apron, said overlapping parts of the folds being adapted to provide holders for said hook. 25

5. A fastener for connecting two opposed parts of an apron, one of said parts being provided with a fastening element, a flexible elongated pad adapted to be secured to that part of the apron opposite to said fastening element, said pad consisting of a fabric strip wound spirally upon itself to provide overlapping folds, rows of stitches connecting the folds near their edges, the overlapping parts of said folds providing pockets adapted to receive said fastener-element. 30 35

In testimony whereof, we have affixed our signatures.

GLEN L. POPE.
